VENETIAN BLIND TILTER

Jules Nisenson, New York, N. Y., assignor to
 Unit Venetian Blind Supply Co., New York,
 N. Y., a corporation of New York

Application January 17, 1939, Serial No. 251,399

6 Claims. (Cl. 156—17)

This invention relates generally to Venetian blinds and more particularly to a tilting mechanism for tilting the slats of the blind.

- Among the objects of the present invention 5 is the provision of a unitary tilting mechanism which in the process of construction may be readily modified so that the same may be utilized to actuate a tilt bar from either the left or right side thereof.
- 10 Another object of this invention is the provision of a tilting mechanism which is readily actuated either by cord or bead chain, and in which novel means are utilized for the retaining and guiding of said cord or chain in operative connection with the main driving pulley thereof.

A still further object of the invention is the provision of a tilting mechanism requiring a minimum of parts, which are either stampings or automatic screw machine products and which 20 require a minimum of labor and expense to assemble.

Another object of the invention lies in the provision of a novel bearing structure for the worm shaft in a Venetian blind tilter.

25 A further object herein lies in the provision of structure which is simple, light in weight, strong, efficient and smooth and full-proof in operation.

These objects and further features and advantages will more fully appear in the progress of this disclosure and as pointed out in the appended claims.

In the accompanying drawing, similar reference characters designating corresponding parts 35 throughout the several views in which:

Fig. 1 is a view in perspective showing a first embodiment of the invention. In this view the cord guide is shown in its closed position and the tilter is arranged to drive a tilt bar from the left end thereof.

40 Fig. 2 is a front elevational view of the embodiment shown in Fig. 1.

Fig. 3 is an elevational view as seen from the right side of Fig. 1.

45 Fig. 4 is a view taken similarly to Fig. 2 showing the cord guide in an open position.

Fig. 5 is a view taken similarly to Fig. 2 showing a second embodiment of the invention.

Fig. 6 is a vertical sectional view as seen from 50 the plane 6 on Fig. 3.

Fig. 7 is a vertical sectional view as seen from the plane 7 on Fig. 2.

Fig. 8 is a vertical sectional view as seen from the plane 8 on Fig. 3.

55 Fig. 9 is a view taken similarly to Fig. 8 with

the cord guide, however, shown in the open position thereof.

Fig. 10 is an enlarged elevational view of one of the bearings shown in section in Fig. 7.

Fig. 11 is a bottom plane view of Fig. 2. 5

Fig. 12 is an enlarged elevational view of the gear-shaft.

Turning to the first embodiment of the invention illustrated in Figs. 1 to 4, and 6 to 12 inclusive, the tilting mechanism generally represented by numeral 10, is substantially enclosed in a housing 11 composed of casing plates 12 and 13. The left casing plate 12 is slightly taller than the right casing plate 13 and both of said plates are each provided with orificed mounting plates 14 and 15 respectively. The mounting plate 14 is preferably integral with the casing plate 12 and forms an angle of ninety degrees therewith. The mounting plate 15 is preferably integral with the casing plate 13 and forms an angle of ninety degrees therewith. Plates 13 and 15 are preferably connected by a reinforcing portion 16, forming an angle of forty-five degrees with each of said plates. As stated above, the mounting plates 14 and 15 are each provided with 25 a pair of orifices 17 (see Fig. 11) which are so positioned that they become aligned when the plates 12 and 13 are in operative position. The holes 17 may then be penetrated by known screws 30 in order to secure the tilting mechanism 10 to the under surface of a Venetian blind head-bar.

The casing plates 12 and 13 in the upper portion thereof are provided with aligned orifices (Figs. 6 and 7). The rivet 19 serves to maintain the upper portions of the plates 12 and 13 in 35 operative connection. The lower portions of the plates 12 and 13 are maintained in position by the gear shaft 20 as will be more particularly set forth below. The gear 21 is provided with a central rectangular orifice 22 which is of sub-

stantially the same size as the exposed portion 23 of the gear shaft 20 which is also rectangular in cross section. The gear carrying portion or hub 24 of the gear shaft 20 is rounded off at the corners thereof to form bearing portions 25. It 40 may thus be seen that with the gear 21 mounted upon the hub 24, the gear is keyed to the gear shaft 20 yet is slidable therealong. The hub 24 is trunnioned in an orifice 26 in the casing plate 13 while the integral longitudinally extending boss 27, circular in cross-section, is rotatably mounted in the orifice 28 in the casing plate 12 (Figs. 6, 7 and 11).

The corners of the gear shaft 20 project outwardly from the central longitudinal axis of the 45

gear shaft an amount sufficient so that the smallest distance between any two opposed pairs of corners will be greater than the diameter of the orifice 26. (Fig. 1). The outer end of the boss 27 is spun or swaged over so that the gear shaft 20 acts similarly to a rotatable rivet to maintain the two casing plates 12 and 13 in spaced operative relation. The two casing plates 12 and 13 adjacent the gear shaft 20 are spaced either by the 10 particular formation of the plates themselves (Fig. 8) or by the thickness of the gear 21. A known angle plate (not shown) having an orifice corresponding to the exposed portion 23 of the gear shaft 20 may be slidably keyed upon said 15 gear shaft and may be suitably affixed to a tilt bar as is known in the Venetian blind art. Rotation of the gear 21 will thus be communicated to the tilt bar of the Venetian blind whereby slats may be tilted as desired, as is well known in the 20 art. A worm shaft 30 is circular in cross-section substantially throughout the length thereof, except the forward end which comprises a head 31 and a rectangular shank portion 32. A pair of 25 concave discs 33 and 34 are provided with rectangular orifices of a size corresponding to the portion 32. With the convex surfaces of the discs 33 and 34 facing each other, these discs are placed over the rear end 35 of the worm shaft 30 and are seated upon the shank portion 32. The 30 corners of the shank portion 32 are spread by a pressing operation which results in securely affixing the discs 33 and 34 to the forward end of the shaft 30. The middle portion of the shaft 30 is provided with opposed outwardly extending 35 longitudinally directed keys 36 (Fig. 6) which are adapted to engage the bore of the worm 37. It may thus be seen that the concave discs 33 and 34 form a pulley 38 which is affixed to the shaft 30 and that the worm is also affixed to the shaft 40 30 and thereby rotates with said pulley.

The worm shaft 30 is rotatably supported by a pair of eyelet bearings 39 and 40 which are mounted by being engaged by and between the casing plates 12 and 13. The casing plate 12 includes an outwardly extending semi-cylindrical portion 42 and a pair of vertically directed grooves 43 and 44. The casing plate 13 includes an outwardly extending semi-cylindrical portion 45 and a pair of vertically extending grooves 46 and 47. 45 The grooves 43, 44 and 46, 47 are preferably formed by pressing into the sheet stock from which the plates 12 and 13 respectively are fabricated. These grooves thus form beads 48, 49 and 50, 51 respectively on the exposed surfaces 50 of said plates. The bearings 39 and 40 are uniform and a description of the bearing 39 will suffice for both. Bearing 39 (Fig. 10) comprises a central cylindrical portion 52, a narrow peripheral flange 53, a wide peripheral flange 54 having a dished edge 55 extending parallel to the cylindrical portion 52. The edges 55 of the bearings 39 and 40 are each engaged by the grooves 43, 46 and 44, 47 respectively and are securely held in place by the compression of the plates 12 and 13 thereabout caused by the rivet 19 and the gear shaft 20 as has been described above. It may be noted at this point that the grooves 43, 44, 46, 47 and their respective external beads 48, 49, 50 and 51 not only serve to provide a simple and efficient 60 anchorage for the bearings 39 and 40 but also materially aid in stiffening the plates 12 and 13 and also in improving of the external appearance thereof.

A perusal of Fig. 7 shows that the bearings 39 and 40 are prevented from moving longitudinally

of the worm shaft 30 and the oppositely disposed narrow peripheral flanges 53 on the inner ends of the central portions 52 abut or lie very close to the outer ends of the worm 37.

Since the worm 37 is integrated with the shaft 5 30 by being a force or drive fit thereon, it may thus be seen that the bearings 39 and 40 act to continuously position the worm 37 in cooperative engagement with the gear 21 and also prevent undue movement of the pulley 38 toward or away 10 from the front edges of the housing 11. The bearings 39 and 40 by reason of their novel eyelet type construction may be made of comparatively light stock yet will possess adequate strength to support the shaft 30 and to properly space the 15 same from the inner surfaces of the semi-cylindrical portions 42 and 45. Bearings 39 and 40 are preferably composed of brass or other material which will form a good bearing surface for 20 cooperation with the particular metal of which the shaft 30 is composed as for example, steel. The wide flange portions 54 of the bearings 39 and 40 also serve to close the end openings of the central channel formed by the inner opposed 25 surfaces of the semi-cylindrical portions 42 and 45 so that dust and dirt are prevented from entering therein and suitable lubricating material, preferably of a high viscosity, may be coated upon the worm shaft at the time the tilting mechanism 10 is constructed. While there exists a 30 space between the lower portions of the plates 12 and 13 between which the gear 21 is disposed, this space or opening is downwardly directed so that there is very slight tendency for dust and dirt to settle in the channel formed by the portions 42 and 45 and enclosed between the bearings 39 and 40. 35

Turning now in particular to the cord or chain guide generally indicated by numeral 60, the same is preferably formed from sheet stock of suitable 40 thickness and includes a body portion 61 having a central orifice 72, symmetrical and oppositely disposed lateral cord guides 62 and 63 and a rearwardly extending peripheral flange 64. The flanges 62 and 63 comprise pulley conforming portions 45 65 and 66 and guiding portions 67 and 68. The cord guide 60 is loosely disposed upon the worm shaft 30 between the forward edges of the plates 12 and 13 and the rear pulley disc 34. The upper portions of each of the plates 12 and 13 50 are provided with inwardly or rearwardly extending notches 69 and 70 respectively. Notches 69 and 70 are so disposed that they become aligned when the plates 12 and 13 are placed together in operative position forming a locking notch 71. 55 By reason of the large size of the orifice 72, the cord guide 60 is supported when in a vertical position by resting upon the lower surface 73 of the notch 71. This position is clearly shown in Fig. 8. When the cord guide 60 is rotated through 60 approximately ninety degrees in either direction from the vertical position shown in Fig. 8, the cord guide 60 may be laterally or horizontally displaced so that ample clearance exists between the outer peripheral edges 74 of the pulley 38 and 65 the pulley conforming portions 65 and 66. With this clearance existing, it is a very simple matter to place an operating cord or chain (not shown) into engagement with the pulley 38.

If the cord guide 60 as viewed in Fig. 2 is manually grasped and rotated through approximately ninety degrees to the left, it will appear as seen in Fig. 4 or from the rear as seen in Fig. 9. The rotation of the cord guide 60 as just described, causes the peripheral flange 64 to drop off of the 75

lower surface 73 and the cord guide 60 becomes relatively unsupported. When the cord guide 60 is moved horizontally to the left the ends of the flange 64 contact the forward edge of the casing plate 13 while the central lower or inner surface of the flange 64 will contact the forward edge of the outer surface of the semi-cylindrical portion 45. The orifice 72 is sufficiently large so that the edge thereof does not at any time contact the shaft 39, though it is of course possible by reducing the size of the orifice 72 to have the edge of the orifice act as a stop by abutting the shaft 39 instead of having the ends and inner or lower surfaces of the peripheral flange 64 serve as such.

To return the cord guide 60 to its original vertical position, it is only necessary to slightly raise the same and to rotate it through ninety degrees in a direction opposite to that originally utilized. The weight of the cord lock and the fact that most of the weight is concentrated in the lower portion thereof tends to keep the same in a normal vertical or closed position. Furthermore when the cord or chain has been wound about the pulley 38, the weight of the hanging cord or chain acts also to keep the cord guide 60 in its vertical or closed position.

Where the present tilting mechanism 10 is utilized in the construction of completely assembled Venetian blinds which are subsequently shipped to another point for installation, and the tilter cord is placed upon the pulley 38 prior to shipment, it may be desirable to temporarily lock the cord guide 60 in its closed position. For this purpose, the lower edge 75 of the cord guide 60 is provided with a pair of spaced notches 76 and 77 leaving a locking tab 78 therebetween. The tab 78 may be bent inward slightly so that the same will take a position indicated by dotted lines on Fig. 7. The tab 78 will then lie between the two forward edges of the casing plates 12 and 13 and will positively prevent the rotation of the cord guide 60. When it is desired to replace the cord after wear, or when it is desired to restore the cord guide to gravity operation, it is only necessary to bend the tab 78 forward an amount sufficient so that it clears the forward edges of the casing plates 12 and 13.

The cord guide 60 while it is securely maintained in place by the structure described above, that is to say when it is "locked" or "gravity acting", still has enough play with relation to the pulley 38 and the casing 11 so that it may be shifted slightly to accommodate any irregularities in cord diameter and so that it may not bind at any time to prevent smooth operation of the pulley 38.

Turning now to the second embodiment of the invention illustrated in Fig. 5, it may be seen that this construction is in a large measure similar to the first embodiment as described, with the exception that lying in front of the body 61 and rearwardly of the pulley 38 there is a locking member 79. Locking member 79 is preferably composed of a resilient material as for example, spring steel and at the upper end thereof is provided with an orifice 80 which permits the locking member 79 to be rotatably supported upon the shaft 39. The lower end of the locking member 79 projects downwardly between the portions 81 and 82 and is thereby prevented from rotating (beyond a slight amount of play) separately from the cord guide 60. The lower portion of the locking member 79 is provided with a rearwardly extending detent 81 preferably formed integral with the member 79. The member 79 is slightly

rearwardly bent so that when the cord guide 60 is in the vertical or closed position thereof, the detent 81 is adapted to lie between the forward lower edges of the plates 12 and 13. The action of the locking member 79 thus serves to prevent rotation of the cord guide 60 unless the member 79 is manually sprung forwardly and rotated. With the detent 81 becoming disengaged the entire cord guide 60 and locking member 79 may be rotated for example to a position indicated by the dot-dash lines in Fig. 5.

The assembly of the various components into a complete mechanism is a simple and rapid procedure. The following method has been found satisfactory. The worm shaft 30 has placed upon it, two concave discs 33 and 34 with their convex surfaces in contact and these are secured in place against the forward end or head 31 of shaft 30 by expanding the rectangular shank portion 32. The cord guide 60 is placed upon shaft 30 with the flange 64 facing away from the pulley 38. If the locking member 79 is utilized in the particular embodiment being assembled, this is placed on the shaft 30 between the pulley 38 and the cord guide 60. The bearing 39 is next placed on the shaft 30 with the wide flange 54 toward the pulley 38. The worm 37 is placed upon the shaft 30 and forced into the desired position where it is positively engaged by the keys 36. The frictional engagement between the keys 36 and the inner bore of the worm 37 is sufficient to prevent both movement of the worm about the shaft 30 and also longitudinally thereof. The bearing 40 is next placed upon the shaft 30 with its wide flange 54 facing away from the pulley 38.

The casing plate 13 next has the gear shaft 20 placed therein with the exposed portion 23 extending in the same direction as the mounting plate 15. The gear 21 is placed upon the gear carrying portion 24 of the shaft 20. The worm shaft assembly previously described is next placed upon the casing plate 13 with the dished edges 55 of the bearings 39 and 40 in the grooves 46 and 47 respectively. The casing plate 12 is next placed upon the previously assembled parts so that the dished edges 55 of the bearings 39 and 40 engage the grooves 43 and 44 respectively. The rivet 19 is placed through the orifices therefor in the upper portions of the plates 12 and 13 and is spun or pressed to form the second head and hold the plates together. The boss 27 is then spun or swaged over thereby bringing the lower portions of the plates 12 and 13 into operative position.

When the plates 12 and 13 are in operative position, the pressure existing between said plates is sufficient to positively secure the bearings 39 and 40 and prevent the same from turning. The casing plates also serve to properly align these bearings so that a smooth running fit is obtained for the shaft 30. Sufficient clearance exists between the two opposed inner surfaces of the semi-cylindrical portions 42 and 43 so that the worm may turn without any interference therefrom.

It may now be seen that there has been provided a simple and efficient tilting mechanism for Venetian blinds which is compact, sturdy, full-proof and inexpensive; and which has novel and desirable features of construction and operation. The foregoing disclosure is to be regarded as descriptive and illustrative only, and not as restricted or limitative of the invention, of which obviously an embodiment may be constructed in

cluding modifications without departing from the general scope herein indicated and in the appended claims.

Having thus described my invention, what I claim as new and desire to secure by Letters Patent, is:

1. In a Venetian blind tilting mechanism having a pulley adapted to be engaged by a flexible element such as a cord or chain: a movable guide for said flexible element adapted in a first position thereof to maintain said flexible element in operative contact with said pulley, and in a second position thereof to lie spaced from said pulley whereby the flexible element may be removed entirely from the pulley or replaced; a frame element such as a casing; means on said guide slidably supported by said frame element when the said guide is in the first position thereof.
2. In a Venetian blind tilting mechanism having a pulley adapted to be engaged by a flexible element such as a cord or chain: a movable guide for said flexible element adapted in a first position thereof to maintain said flexible element in operative contact with said pulley, and in a second position thereof to lie spaced from said pulley whereby the flexible element may be removed entirely from the pulley or replaced; a frame element such as a casing; means on said guide slidably supported by said frame element when the guide is in the first position thereof; said guide being relatively unsupported when in the second position thereof and limited in movement away from the pulley by said means engaging a portion of said frame element different from the portion of the frame element which supports said means when the guide is in the first position thereof.
3. In a Venetian blind tilting mechanism having a pulley adapted to be engaged by a flexible element such as a cord or chain: a movable guide for said flexible element adapted in a closed position thereof to maintain said flexible element in operative connection with said pulley, and in an open position thereof to lie spaced from said pulley whereby the flexible element may be removed entirely from the pulley or replaced; a frame element such as a casing; a flange on said guide slidably supported by a first portion of said frame element when the guide is in the closed position thereof; said flange being loosely supported when in the open position thereof and limited in movement away from the pulley by reason of the flange acting as a detent and engaging a second portion of said frame element.

4. In a Venetian blind tilting mechanism having a pulley adapted to be engaged by a flexible element such as a cord or chain: a movable guide element having lateral guiding flanges extending forwardly therefrom and a rearwardly extending peripheral flange, said guide element and said lateral guiding flanges being adapted in the closed position thereof to maintain said flexible element in operative engagement with said pulley and in an open position thereof to have the lateral guiding flanges spaced from said pulley whereby the flexible element may be removed entirely from the pulley or replaced; a frame element; said peripheral flange on the guide element being slidably supported by said frame element when the guide element is in the closed position thereof and loosely supported when in the open position thereof and limited in movement away from the pulley by reason of the peripheral flange acting as a stop when the same engages the frame element.

5. In a Venetian blind tilting mechanism having a pulley adapted to be engaged by a flexible element such as a cord or chain: a movable guide for said flexible element adapted in a first position thereof to maintain said flexible element in operative contact with said pulley, and in a second position thereof to lie spaced from said pulley whereby the flexible element may be removed entirely from the pulley or replaced; a frame element such as a casing; first means associated with said guide and movable therewith, and adapted to engage said frame element and thereby to maintain the guide in the first position thereof; second means on said guide slidably supported by said frame element when the guide is in the first position thereof.

6. In a Venetian blind tilting mechanism having a pulley adapted to be engaged by a flexible element such as a cord or chain: a movable guide for said flexible element adapted in a first position thereof to maintain said flexible element in operative contact with said pulley, and in a second position thereof to lie spaced from said pulley whereby the flexible element may be removed entirely from the pulley or replaced; a frame element such as a casing; first means on said guide slidably supported by said frame element when the guide is in the first position thereof; and second means associated with said guide and movable therewith, adapted to engage resiliently said frame element and thereby to maintain the guide in the first position thereof.

JULES NISENSON. 55
